Term of patent 14 years

(Cl. D34—5)

To all whom it may concern:

Be it known that we, Donald E. Hackett, Jr., and Arthur H. Giorla, citizens of the United States, both residing at Lawrence, in the county of Essex and State of Massachusetts, have invented a new, original, and ornamental Design for a Ball Throwing Game Target or Similar Article, of which the following is a specification, reference being had to the accompanying drawing, forming part thereof.

Fig. 1 is a perspective view of a ball throwing game target or similar article, showing our new design;

Fig. 2 is a top plan view thereof; and

Fig. 3 is a front elevational view thereof.

The side of the article not shown has substantially the same appearance as the side shown in Fig. 1.

We claim:

The ornamental design for a ball throwing game target or similar article, as shown and described.
